UNITED STATES PATENT OFFICE.

FREDERICK FISCHER, OF BUFFALO, NEW YORK, ASSIGNOR OF ONE-HALF
TO HENRY C. STEUL, OF SAME PLACE.

DESIGN FOR A CIGAR-REST AND ASH-RECEIVER.

SPECIFICATION forming part of Design No. 35,136, dated October 1, 1901.

Application filed May 29, 1901. Serial No. 62,434. Term of patent 3½ years.

To all whom it may concern:

Be it known that I, FREDERICK FISCHER, a citizen of the United States, and a resident of Buffalo, in the county of Erie and State of New York, have invented and produced a new and original Design for a Cigar-Rest and Ash-Receiver, of which the following is a specification, reference being had to the accompanying drawings, forming a part thereof.

This invention relates to a combined cigar-rest and ash-receiver, and is characterized by the contour and relative arrangement of the surfaces comprising it and as shown in the accompanying drawings, forming a part of this specification.

Figure 1 illustrates a top plan view of the design. Fig. 2 is a transverse sectional view on the line *x x* of Fig. 1, and Fig. 3 is a central longitudinal section of the design.

The invention consists, essentially, of a shallow circular receptacle 1, the side wall thereof being inclined downwardly. Projecting outwardly from the receptacle and almost in a horizontal plane therefrom is a handle 2, having its upper face concaved and ter-

minating at its free end in a downwardly-directed portion 5, which is curved back upon itself, as at 6, and which is substantially in a vertical plane and at right angles to the handle 2.

Disposed upon each side of the handle 2 are ears 3 and 4, which are formed with the handle and so curved as to correspond with the contour of the concaved face thereof.

By this design I have produced a cigar-35
rest and ash-receiver in a single structure
and one that is light, durable, cheap, and of
neat and pleasing appearance.

Having thus described my invention, what
I claim, and desire to secure by Letters Pat-40
ent, is—

The design for a cigar-rest and ash-receiver,
as herein shown and described.

In testimony that I claim the foregoing as
my own I affix my signature in the presence 45
of two subscribing witnesses.

FREDERICK FISCHER.
